(57) **CLAIM**

The ornamental design for an implement holder, as shown and described.

DESCRIPTION

FIG. 1 is a perspective view of an implement holder.

FIG. 2 is a top plan view of the implement holder of FIG. 1.

FIG. 3 is a bottom plan view of the implement holder of FIG. 1.

FIG. 4 is front elevation view of the implement holder of FIG. 1.

FIG. 5 a rear elevation view of the implement holder of FIG. 1.

FIG. 6 is a left side view of the implement holder of FIG. 1; and,

FIG. 7 is a right side view of the implement holder of FIG. 1.

The broken lines in the figures illustrate the portions of the implement holder that form no part of the claimed design. The dash-dot-dash lines immediately adjacent to the shaded areas in the figures represent the boundaries of the claimed design. None of the broken lines form any part of the claimed design.
